UNITED STATES PATENT OFFICE.

ANDREW C. CAMPBELL, OF WATERBURY, CONNECTICUT, ASSIGNOR TO AMERICAN CHAIN COMPANY, INC., A CORPORATION OF NEW YORK.

PUNCHING MACHINE.

Application filed September 6, 1924. Serial No. 736,342.

This invention relates to reciprocating punching tools, and more particularly to machines of the type known as "nibblers", although I contemplate the use of my improvements in any field for which they are adapted by their nature. The object of the invention is to provide a machine of the above type with a device in the nature of a latch or coupler serving to control the range of movement of the tool-carrier relatively to the work-support. Provision is made for manual operation of the coupler so that it can be withdrawn when it is desired to raise the tool completely from the work to permit the work to be cleared, for observation, or to be shifted on the work-support so that operation can be started at a different region of the work.

Provision is also made for adjustment of the tool-carrier relatively to its actuating devices, and for a more extended clearance of the tool to permit such an operation as the re-adjustment or sharpening of the tool, or its removal and replacement, or the substitution of another tool therefor, or any other necessary or desirable operation requiring a more extensive movement of the tool relatively to the work-support than is involved in the conventional punching operation.

30 Referring to the drawings,

Figure 1 is a side view, partly in vertical section, of a "nibbler" or punching machine in the construction of which the invention has been embodied.

35 Figure 2 is a fragmentary detail view, in section, like the corresponding part of Figure 1, but showing the parts on a larger scale, in a position different from that illustrated in Figure 1.

40 Figure 3 is a view on a larger scale, in horizontal section on the line III-III of Figure 1, and shows the latch in its coupling position.

45 Figure 4 is a similar view of the latch in another position withdrawn to permit the tool to be cleared from the work.

In the illustrated embodiment, the reference character 1 designates the frame of the punching machine, carrying the anvil or work-support 2 in which is seated the female die 3 of a punch, secured in place by a set-screw 4, and 5 designates a punching-tool provided with a pilot 7 which guides the work as the operation of "nibbling" or 55 punching proceeds under the reciprocatory

movement of the tool-carrier 8, within the lower end of which the tool 5 is secured by a set-screw 9 passing through a bushing 10. The tool carrier 8 reciprocates in a vertical bore 11 of the head 1 and derives its movements from a shaft 12, by means of a crank 13 which acts upon a slide 14 working in an enlarged upper continuation 15 of the bore 11, and this slide is connected with the tool-carrier 8 by a rod 16, the lower end 17 of the latter being screwed into a socket 18 of the tool-carrier, while the upper part 16 passes upwardly through a central bore 19 of the slide 14, to which it is connected against relative rotation by a detent 20 having a nose 21 taking into a groove 22 formed on the under surface of a handle 23 pinned to the rod 16 at 24. By turning the handle 23 the rod 16 and its screw-threaded part 17 are turned to lengthen or shorten the reach 75 of the tool-carrier 8 and its tool 5.

The connection between the tool-carrier 8 and the slide 14 is completed by a latch or coupler 25 having a body-portion which is U-shaped preferably in plan view, as shown 80 in Figures 3 and 4, with legs 27 preferably bevelled at 28, as shown in Figure 2, for engagement slidingly with the undercut ways 29 formed in the lower end of the slide 14, and having a crotch 31, with shoulders 32 85 adapted to fit snugly over a shoulder 33 formed on the rod 16, for a purpose now to be described in accordance with this invention.

The coupler or latch 25 works in a slot 34. 90 of the head 30 and moves up and down therein with the slide 14, and when the latch is inserted between the lower end of the slide 14 and the collar 33 on the rod 16, so that the shoulders 32 of the latch are in the position shown in Fig. 3, movement of the crank 13 downward will force the shoulders 32 against the shoulder 33 of the rod 16 to press it downward, accompanied by the tool-carrier 8 and the tool 5. Upward movement of the 100 crank 13 will raise the slide 14, which will elevate the handle 23, drawing up the rod 16, tool-carrier 8 and tool 5, the collar 33 engaging the latch shoulders 32 so that the latch serves as an abutment to limit upward movement of the rod 16, tool-carrier 8 and tool 5, relatively to the slide 14.

This is the position illustrated in Figure 1, and the effect of this relation of the parts is to prevent the pilot 7 of the tool 5 from 110

- being cleared from the work. In accordance with my invention, however, the latch 25 may be readily withdrawn to the position shown in Fig. 4, which clears the shoulders 5 32 from the path of the shoulder 33 on the rod 16, so that then, by grasping the handle 23, the operator can raise the rod 16, tool-carrier 8 and tool 5, to clear the pilot 7 from the work. This upward movement of the 10 rod 16 would soon be checked by engagement of the collar 33 with the under surface of the slide 14, so that I prefer to provide a recess 36 in the under surface of the slide 14, to permit longer relative movement between the rod 16 and slide 14, so that the 15 work can be exposed sufficiently for observation, and can be shifted on the work-support for the purpose of starting operation at a different region of the work.
- 20 The tool 5 can also be withdrawn further for observation and repair or replacement, by rotation of the handle 23, so that the threaded portion 17 of the rod 16 is turned within the threaded socket 18 of the tool-carrier 8 until the tool is clear not only of the work, but also clear of the foot or guide 37. The latter is mounted on a sliding post 38 adjusted by a screw 39 and held by a clamp 40.
- 25 In order to resume the nibbling operation, it is only necessary to set the rod 16 at its lower position while the slide 14 is held in a relatively high position by the crank 13, so that the shoulders 32 can readily enter between the shoulder 33 on rod 16 and the bottom of slide 14, when the coupler 25 is pushed inward, after which the slide 14 and tool-carrier 8 will be reciprocated by the 30 crank 13, being coupled together firmly by the latch 26 as shown in Fig. 1, hereinbefore described.
- Having thus described my invention, I claim:
1. In a machine of the class described, the combination with a frame provided with a work support, of a slide having two parts movable relatively to each other, a tool-carrier connected with one of said slide parts for operation thereby, means to reciprocate said slide, and means connecting said slide parts, said means being adapted to effect adjustment between said slide parts, and also arranged to permit relative axial play therebetween at times, and a manually operable coupling device to prevent said play at the will of the operator.
  2. In a machine of the class described, the combination with a frame provided with a work support, a tool-carrier, a slide and means to reciprocate said slide, of a rod connecting said slide and tool-carrier with a certain amount of play therebetween, and means to take up said play at the will of the operator, said means comprising a shoulder on said rod and a coupling device sup-

ported by said slide in position to be introduced between said slide and said shoulder.

3. In a machine of the class described, the combination with a frame provided with a work support, a tool-carrier, a slide and 70 means to reciprocate said slide, of a rod connecting said slide and tool-carrier with a certain amount of play therebetween, and means to take up said play at the will of the operator, said means comprising a shoulder 75 on said rod and a coupling device supported by said slide in position to be introduced between said slide and said shoulder, said tool-carrier and slide having means to permit relative axial adjustment therebetween 80 by rotation of said rod independently of its co-operation with said coupling device.

4. In a machine of the class described, the combination with a frame provided with a work-support, a tool-carrier, a slide and 85 means to reciprocate said slide, of a rod connecting said slide and tool-carrier with a certain amount of play therebetween, and means to prevent said play at the will 90 of the operator, comprising a latch supported in ways on the bottom of said slide in position to be moved transversely into coupling engagement with said rod, and movable in reverse direction to permit said play.

5. In a machine of the class described, the combination with a frame provided with a work-support, a tool-carrier, a slide and means to reciprocate said slide, of a rod connecting said slide and tool-carrier with a 100 certain amount of play therebetween and means to prevent said play at the will of the operator, comprising a U-shaped latch supported in ways on the bottom of said slide in position to embrace said rod, and movable 105 transversely into and out of coupling engagement therewith.

6. In a machine of the class described, the combination with a frame provided with a work-support and having a head provided with a slideway, a slide and a tool-carrier mounted to reciprocate co-axially in said slide and tool-carrier, a rod connecting said slide and tool-carrier with an allowance for axial play therebetween, and a coupling-device mounted on said slide and having a handle, extending out through an aperture in said head, by which said coupling device may be moved transversely of said head into coupling engagement with said rod, to prevent said play between said slide and tool-carrier; said rod being screwed into said tool-carrier and extending freely upward therefrom through said slide, presenting above said head a portion operable manually 110 to rotate said rod, whereby it may be screwed into said tool-carrier more or less, to vary the relative axial positions of said slide and tool-carrier, and means to control rotation 115 of said rod.

7. In a machine of the class described, the combination with a frame provided with a work-support, a tool-carrier, a slide and means to reciprocate said slide, of a coupling-rod situated in aligned bores formed within said slide and tool-carrier, said rod being arranged to connect said slide and tool-carrier, with a certain amount of play therebetween, and means to prevent said play, at the will of the operator, comprising a collar on said rod and a latch supported by said slide in position to be introduced between said slide and said collar, said slide having in its under surface an enlargement of said bore to accommodate said collar when said rod is released by withdrawal of said latch.

adapted for adjustment relatively to each other, and a tool-carrier mounted on one of said parts to reciprocate therewith in said slideway, a member connecting said slide parts with an allowance for axial play therebetween, and a coupling device mounted on said slide and having a handle, extending out through an aperture in said head, by which said coupling device may be moved transversely of said head into coupling engagement with said slide to prevent said play between the parts of said slide, said connecting member being connected with one of said slide parts and extended freely therefrom through the other part of said slide, presenting beyond the latter a portion operable manually to vary the relative axial positions of said slide and tool-carrier.

8. In a machine of the class described, the combination with a frame provided with a work-support and having a head provided with a slideway, a slide having two parts movable together in said slideway and

In witness whereof, I have signed this specification.

ANDREW C. CAMPBELL.
